Primary Examiner—Martie K. Holtje**[57] CLAIM**

The ornamental design for an erasable door knob tag with marker-pen holder, as shown and described.

DESCRIPTION

FIG. 1 is a front elevation view of an erasable door knob tag with marker-pen holder showing my new design;

FIG. 2 is a side elevation view, the other side being a mirror image thereof;

FIG. 3 is a bottom plan view thereof;

FIG. 4 is an enlarged fragmentary cross-sectional view of the perforation taken along lines 4—4 of FIG. 1;

FIG. 5 is a top plan view thereof;

FIG. 6 is a rear view thereof;

FIG. 7 is a perspective view of FIG. 1 thereof;

FIG. 8 is a perspective view of FIG. 1 in use with a marker-pen placed in the pen holder thereof;

FIG. 9 is a second embodiment of FIG. 1, it being understood that the undisclosed top, left-side, right-side and bottom views the same as in FIGS. 2, 3 and 5;

FIG. 10 is a perspective view of the second embodiment; and,

FIG. 11 is a rear view of the second embodiment thereof.

The broken lines showing the outlines of a marker-pen on FIG. 8 are for illustrative purposes only and form no part of the claimed design.
